UNITED STATES PATENT OFFICE.

CHARLES WASSER AND RUSSELL W. WIRSHING, OF DAYTON, OHIO, ASSIGNORS TO THE MIAMI MANUFACTURING COMPANY, OF DAYTON, OHIO, A CORPORATION OF OHIO.

SOAP CUTTER.

Application filed August 18, 1921. Serial No. 493,361.

To all whom it may concern:

Be it known that we, CHARLES WASSER and RUSSELL W. WIRSHING, citizens of the United States, residing in the city of Dayton, county of Montgomery, and State of Ohio, have invented certain new and useful Improvements in Soap Cutters, of which the following is a specification.

The principal object of our invention is 10 to provide a simple, compact and economical device that is adapted to be attached to a table or other object for easily and efficiently cutting or shaving soap.

It is another object of our invention to 15 provide simple and efficient clamping means for easily and firmly securing our soap cutter to a table or other object.

Other important and incidental objects will be brought out in the following specification and particularly set forth in the subjoined claim.

In the drawings, Figure 1 is a top plan view, partly broken away, of our soap cutter. Figure 2 is an end view thereof. Figure 3 25 is a side elevational view of the same. Figure 4 is a bottom plan view of the cutting disc. And Figure 5 is a side view of the latter in its inverted position.

Throughout the specification and drawings, similar reference characters denote corresponding parts.

Referring to the accompanying drawings for a detailed description of one form of embodiment of our invention, the numeral 1 35 designates a ring member constructed of aluminum or other suitable metal, having a top inwardly projecting flange portion 2 that is annular in shape. Projecting downwardly from one side of the ring member 1 40 is a relatively flat supporting portion 3.

Adapted to be fitted upon the ring member 1 is a cover 4 constructed of aluminum or other suitable metal. This cover 4 has a downwardly projecting annular rim portion 45 5 that is adapted to fit against the side periphery of the ring member 1, and is secured to the flange portion 2 of the latter as follows: Provided in the said flange portion 2 of the ring member 1, are two slots 6, 6 50 preferably about 180° apart. Adapted to enter each one of these slots 6, 6, is an approximately right-angled tongue 7 that is turned down from the cover 4. When the latter is applied to the ring member 1, with 55 the tongue portions 7, 7 within their respec-

tive slots 6, 6 in said ring member, the cover 4 may be readily turned to bring the free end portions of the tongues 7, 7 under the flange portion 2 of the ring member to firmly hold said cover upon the latter. (See Figures 1 and 2.) While we have provided the means just described for removably connecting the cover to the ring member 1, any other suitable means may be employed for this purpose without departing from the spirit of the invention.

Preferably turned up from the middle portion of the cover 4, is a hopper or soap receiving part 8 that is rectangular in longitudinal section. Resting upon an annular ledge portion 9 of the flange 2 of the ring member 1, a slight distance below the cover 4, is the rim portion of a cutting disc 10. Cut in the latter is a series of radial, triangular slots 11, the piece of metal that formerly filled each slot being turned down at right angles to the disc as shown in Figures 3, 4 and 5. The radial edge 12 of each slot opposite the turned down metal piece 13 thereof, is turned upwardly slightly above 80 the plane of the disc and sharpened to cut or shave the soap that is inserted in the hopper 8 above, when the disc 10 is turned by the means now to be described. One slot 11a extends to the center of the disc to effect 85 a full center cut. The turned down pieces at the edges of the slots act as flanges to direct the flow of shavings to the receptacle beneath.

Provided in the disc 10 near its marginal 90 edge, is a circumferential series of pin holes 14. Adapted to enter these holes from below the disc, are the teeth of a pinion 15 fast on the inner end of a shaft 16 that is journaled in a hollow boss 17 that projects outwardly from the supporting portion 3 of the ring member 1. Secured to the outer end of the shaft 16 is a crank handle 18 which, when turned, will rotate the disc 10, that is free to turn upon the ledge portion 9 of the flange 2. When the disc 10 is rotated, the soap that is cut or shaved by its knife-edged slots 11 will fall through the latter into a receptacle 18a resting upon a table 19 to which the cutting device is secured by the following means:

Referring to Figures 2 and 3, there is riveted or otherwise secured to the supporting portion 3 of the ring member 1, a slightly curved angle-plate 20 whose end portions are 110

at approximately a right angle to each other. Provided in the upper end of the plate 20 is a transverse slot 21 through which there loosely projects a turned-up end 22 of an 5 arched piece 23, the other end of which is slightly rounded to bear against an edge portion of the table 19 or other object.

Projecting loosely through a hole in the middle portion of the angle plate 20 and 10 the arched piece 23, is a screw bolt 24, to whose outer threaded end, beyond the arched piece 23, there is applied a wing nut 25. (See Figures 2 and 3.) After the lower end of the angle plate 20 is brought over, and 15 the lower end of the arched piece 23 is positioned under, the edge portion of the table 19, the wing nut 25 is turned to tightly press the rounded end of the arched piece 23 against the edge portion of the table. The 20 latter will then be tightly gripped by the clamp just described, to firmly hold the soap cutter upon the table. While we employ the above described clamping device for attaching our soap cutter to the table 19, any 25 other suitable means may be employed for

this purpose without departing from the spirit of the invention.

We do not wish to be limited to the details of construction and arrangement herein shown and described, and any changes or 30 modifications may be made therein within the scope of the subjoined claim.

Having described our invention, we claim:

In a device of the type described, the combination with a ring member having a top 35 inwardly projecting flange portion and a supporting portion, of a cover fitted on said ring member, a hopper turned up from the middle portion of said cover, the flange portion of the ring member having an inner 40 annular ledge part, a slotted, cutting disc free to turn upon said ledge part of the ring member below said cover, and means for rotating said disc.

In testimony whereof we have hereunto 45 set our hands this 15th day of August, 1921.

CHARLES WASSER.
RUSSELL W. WIRSHING.

Witness:

HOWARD S. SMITH.
